UNITED STATES PATENT OFFICE

115,565

DESIGN FOR A BOOT

Charles E. O'Donnell, Lynn, Mass.

Application November 7, 1938, Serial No. 80,921

Term of patent 3½ years

To whom it may concern:

Be it known that I, Charles E. O'Donnell, a citizen of the United States, residing at Lynn, in the county of Essex and State of Massachusetts, have invented a new, original, and ornamental Design for a Boot, of which the following is a specification, reference being had to the accompanying drawing, forming part thereof.

In the drawing:

The figure is a perspective view of a boot showing my new design. The design is substantially the same on both sides of the boot.

I claim:

The ornamental design for a boot, as shown and described.

CHARLES E. O'DONNELL.
